UNITED STATES PATENT OFFICE

ARTHUR H. BERNTSON AND CLIFFORD J. ZIMMERMAN, OF SALT LAKE CITY, UTAH

PLIERS

Application filed February 6, 1931. Serial No. 513,825.

This invention relates to pliers for applying ear tags, though not necessarily restricted thereto.

The principal object of the invention is to make a single pair of pliers adaptable for applying ear tags of different sizes or kinds, or for performing a number of different operations.

The characteristic feature of the present invention comprises a rotatable element mounted in one of the jaws of the pliers, said rotatable element having a number of different faces which may successively be brought in operative conjunction with the other jaw for performing predetermined operations.

The features of this invention for which the protection of Letters Patent of the United States is desired, are collectively grouped in the claims concluding this specification.

20 In the drawings, which illustrate several embodiments of this invention,

Fig. 1 represents a vertical center section taken through a pair of pliers with an ear tag in place, ready to be operated upon; parts 25 of the handles being broken away;

Fig. 2, a front elevation, ear tag omitted;

Fig. 3, a section on line 3—3, Fig. 1, parts in the background omitted;

Fig. 4, a view in perspective of the rotatable element, alone;

Fig. 5, a view similar to Fig. 1, showing however, a rotatable element of a different kind;

Fig. 6, a view in perspective of the lower 35 jaw of the kind indicated in Fig. 5;

Fig. 7, a section on line 7—7, Fig. 5, parts in the background omitted;

Fig. 8, a vertical center section similar to Fig. 1, but showing still another construction 40 of the rotatable element and lower jaw; and

Fig. 9, a front elevation of the lower jaw indicated in Fig. 8.

Referring to the drawings, the numeral 20 indicates the lower jaw and the numeral 21 45 the upper jaw of a pair of compound ear tag

pliers having the handles 24 and 25. Jaws 20 and 21 may be pivoted together at 26, while the handles 24 and 25 may be pivoted respectively, to the jaws 20 and 21, at 28 and 29, the handles in turn being pivoted together at 27 to form a fulcrum.

The forward portion 20—1 of the lower jaw has preferably the shape of an open cylinder from which the upper portion of the wall has been removed, as clearly shown in Figs. 2 and 3, thus leaving an open capsule or cradle as a holder for a barrel 30 rotatably disposed therein. The barrel has the bearing portions 31, which fit snugly against the inner cylindrical surface of the jaw portion 20—1.

Each of the bearing portions 31 may have its rear portion notched as indicated at 32, each notch having the tapering mouth 33. Between each pair of bearing portions 31 is a depressed, substantially 50 flat bed 34, 35 and 36. The bed portions 34, 55 35 and 36, respectively, may be provided with the clinching wells 34—1, 35—1, and 36—1, as well as the stop portions 34—2, 35—2 and 36—2.

The forward end of the barrel may 60 be closed by a head 37, which may be soldered, welded, or otherwise fastened in place. The barrel is preferably so arranged that the bearing portion 31 shall be diametrically 65 opposite each one of the beds 34, 35 and 36, 70 thereby being in position to resist the stress manifested when the pliers are closed together in clinching an ear tag.

The barrel 30 may be inserted in the portion 20—1 of the jaw 20, and be fastened 75 therein in any position where a bed shall be at the top of the jaw, by bringing the notched portion 32 of the opposite bearing portion 31 into registry with a bolt 38, which latter passes through a hole 39 in the bottom of the portion 20—1.

The bolt 38 may have a nut 38—1 and a knurled head 38—2.

A disk 40 having the hub 40—1 is rotatably mounted on the fulcrum pin 26, and has the notches 44, 45 and 46, which operatively cor-

respond to the bed portions 34, 35 and 36, respectively.

The disk 40 may be rotated to bring any of the notches 44, 45 and 46, into operative conjunction with the corresponding beds 34, 35 or 36, and be nominally held in each of the conjunctive positions by means of a spring 41 which is fastened at 41-1 to the web 21-1 of the jaw 21. Spring 41 has a curved finger 41-2, which engages the notches 47, 48 or 49 of the disk, as the case may demand.

The purpose of notched portions 44, 45 and 46, is to form back stops for holding tags in operative positions. Clearly, tags of different sizes require notched portions of different sizes.

A second form of this invention is shown in Figs. 5, 6 and 7. In this form, the lower jaw may have the side pieces 50, end piece 51, and the shelf or bracket 52, which latter extends forwardly from the end piece 51. The side pieces 50, end piece 51, and shelf 52, may all be integral with one another, being preferably stamped out of a single plate 25 and afterwards bent into the shape indicated.

A die member 54, pivoted at 56 to the end piece 51, may be rotatable in the shelf 52 and be secured in the desired position by means of a thumb screw 57. The thumb screw 30 may pass through a hole 58 in the bracket, and be secured in any one of the threaded holes 59 corresponding to the particular die, such as 54-1, which at that time may be in the operative position.

35 A third form of the invention is shown in Figs. 8 and 9. In this form, the lower jaw may consist of side pieces 62, integrally connected to the bottom piece 63. A pin 64 may extend transversely through the side pieces 40 62 and have rotatably mounted thereon, a die block 65. The die block has the die faces 65-1, 65-2, 65-3 and 65-4, and may be rigidly positioned in the lower jaw by means of a screw 67 extending through any one of 45 the holes 68, which corresponds to the particular die 65-1 to 65-4 that may be in use.

In the forms shown in Figs. 5 and 8, the centering disks 60 and 70 are similar to the centering disk 40 in Fig. 1, and are nominally 50 held in place by the springs 61 and 71, respectively.

It will be noted that in the forms shown in Figs. 1 and 5, the axes of rotation of the die members are transverse to the pivotal 55 axes of the jaws, while in the form shown in Fig. 8, the axis of the die member is substantially parallel to the pivotal axis.

The closing and clinching of ear tags during the process of applying them to animals, 60 is well known, and hence is not here described in detail.

While desirable specific embodiments of 65 this invention are herein shown and described, it is to be clearly understood that all the detailed parts thereof, are not necessarily

shown in the preferred forms, so that various changes can be made without departing from the spirit and scope of the invention as defined by the following claims in which its essential and characteristic parts are enumerated.

Having fully described our invention, what we claim is:

1. Ear tag pliers, including in combination, 70 two jaws cooperatively pivoted together, a die member having a plurality of ear tag closing and clinching dies rotatably disposed in one of said jaws, and means for nominally holding said die block in various cooperative positions relatively to the other jaw, and a backstop operative to assist in holding ear tags in positions to permit the closing and clinching thereof.

2. Ear tag pliers, including in combination, 75 two jaws pivoted together, a die member rotatable in one of said jaws, said die member having a plurality of die faces operative to close and clinch ear tags, means for nominally fixing said die member in positions where any one of said die faces shall 80 be in cooperative conjunction with the other jaw, and a backstop to assist in holding ear tags in desired positions.

3. Pliers, including in combination, 85 two jaws held in operative relation to each other, a rotatable die member having a plurality of die faces operative in one of said jaws, and a backstop having stop portions corresponding to said die faces, said backstop being 90 adapted for positioning so that any stop portion can be placed in operative conjunction with the corresponding die face of said die member.

4. Pliers, including in combination, 95 two jaws cooperatively pivoted together, one of said jaws being provided with a forwardly extending cylinder having an open portion positioned in opposing relation to the other jaw, and a barrel rotatable in said cylinder, 100 said barrel having a plurality of die faces, each of said die faces being adapted for cooperative registering with the said other jaw.

5. Pliers, including in combination, 115 two jaws cooperatively pivoted together, one of said jaws having a forwardly extending shelf, a die member having a plurality of die faces operatively supported by said shelf, and means for rotatably fastening the die member to the shelf jaw for the purpose of 120 bringing any of said die faces into cooperative relation with the other jaw.

6. Pliers, including in combination, 125 two jaws cooperatively pivoted together, a rotatable die member having a plurality of die faces rotatably disposed in one of said jaws, the axis of rotation of said die member extending substantially transverse to the pivotal axis of said jaws, for the purpose of 130 bringing the various die faces successively

into cooperative conjunction with the other jaw.

7. Ear tag pliers, including in combination, two jaws cooperatively pivoted together, a rotatable die member having a plurality of die faces, rotatably disposed in one of said jaws, the axis of rotation of said die member extending substantially parallel to the pivotal axis of said jaws, for the purpose of bringing the various die faces successively into cooperative conjunction with the other jaw.

In testimony whereof, we sign our names hereto.

15 ARTHUR H. BERNTSON.
CLIFFORD J. ZIMMERMAN.
